UNITED STATES PATENT OFFICE.

NELS L. MALMGREN, OF CHICAGO, ILLINOIS.

STRUT OR COLUMN.

Application filed April 26, 1923. Serial No. 634,797.

To all whom it may concern:

Be it known that I, NELS L. MALMGREN, a citizen of the United States, and a resident of Chicago, in the county of Cook and State of Illinois, have invented an Improved Strut or Column, of which the following is a specification.

This invention relates to struts or columns and relates particularly to struts or columns 10 of the general type which forms the subject-matter of U. S. Letters Patent heretofore issued to me on March 13, 1924, No. 1,486,444.

The strut or column which forms the subject-matter of my said prior Patent No. 15 1,486,444 is particularly designed and adapted for use in concrete building construction for supporting the temporary platforms or false work on which concrete floors are laid, and the object of the present invention is to 20 provide a strut or column of this general type which, in addition to its adaptability for supporting the platforms or false work for concrete floors, may quickly and conveniently be converted into T's for supporting the mold forms for the concrete beams 25 or girders which carry the floors.

Prior to my invention, it was the general practice to provide T's for supporting the beam or girder molds, the cross timbers of 30 which were permanently secured to the upper end of the strut portions thereof and were braced by diagonal braces connecting said timbers and strut portions. This was objectionable owing to the considerable space required for storing and transporting said 35 T's in quantities and because T-struts or columns could not readily be converted or adapted for other uses, where T-struts, as such, could not be used.

To effect the foregoing object, a strut or 40 column embodying my invention and improvements comprises a strut or column comprising a sleeve member, a post member loosely fitted thereto and adapted to telescope therein, and adjustable stop on said 45 sleeve member which forms a rigid abutment for said post member—all as fully set forth and described in my said Patent No. 1,486,444—and separate brackets adapted to 50 be removably attached to the sleeve member of the strut, which preferably are made of steel shapes which may be purchased commercially and which are adapted for supporting cross-timbers, thus providing for 55 quickly and conveniently converting the strut of my said prior application into a T-

strut adapted for supporting molds for beams, girders and the like.

A particular advantage of my improved construction is that the struts or columns 60 may very quickly and conveniently be converted for use either as T's or as plain struts or columns, as may be desired.

A further advantage of my improved construction is the convenience with which T- 65 struts embodying my invention and improvements may be transported and stored as compared with T's, the cross-timbers of which are permanently secured to the uprights thereof, due to the fact that, in accordance with my construction, the brackets which form the cross-supports of the T's can be detached and stored separately, thus rendering them more convenient to handle and also providing for storing and loading 70 them much more compactly and in much smaller space than would be required for T's the cross-timbers of which are permanently secured to the struts or columns proper thereof. 80

In the accompanying drawings, in which my invention is fully illustrated—

Figure 1 is a side view of a strut or column embodying my invention and improvements, shown as applied in use for supporting the mold for forming a concrete beam, girder or the like. 85

Figure 2 is an enlarged view of the upper end of said T-strut and supported structure from the right hand side of Fig. 1. 90

Figure 3 is an enlarged sectional elevation of the upper end of said T-strut, on the line 3—3 of Fig. 1, the cross-timber being removed.

Figure 4 is an enlarged top plan view of 95 my improved T-strut with the cross-timber removed.

Figure 5 is a sectional side view of the upper end of the T-strut shown in Fig. 4, the section being taken on the line 5—5 of 100 Fig. 4.

Figure 6 is a sectional bottom plan view of the column proper on the line 6—6 of Fig. 1.

Figure 7 is a perspective view of a stop-plate for the post member of the strut or column, and 105

Figure 8 is a fragmentary detail view showing the means for attaching the removable brackets to the sleeve section of the 110 T-strut.

In the accompanying drawings I have, for

purposes of clear and definite illustration, shown a **T** strut or column embodying my invention and improvements as applied in use for supporting the mold for forming a concrete beam, girder or the like.

Referring now to the drawings, A designates, as a whole, a **T** strut or column embodying my invention, comprising a sleeve section B, a post section C, brackets D adapted to be detachably connected to the upper end of the sleeve section B; and E designates a mold for a concrete beam or girder, supported on said strut or column.

The sleeve member B consists of four angle bars 1 rigidly connected together in spaced relation by means of transverse members—specifically bands 2—secured to the exterior surfaces thereof at desired distances apart—say nine (9) inches—lengthwise of said sleeve member, the relation being such that the inner surfaces of said angle bars will define a substantially square or rectangular opening extending lengthwise through said sleeve member, having longitudinal openings 3 in its lateral sides.

The post member C preferably consists of a timber of substantially the same shape in cross-section as the opening through the sleeve member B and which is of such size that it will telescope into said sleeve member, being loosely fitted thereto.

In use, the sleeve member B and post member C of my improved strut or column are adapted to be joined to form a strut or column of desired length, by means of a plate 4 which is adapted to be inserted into the interior of the sleeve member B with parts thereof extending through the openings 3 in the sides of said sleeve member between the angle bars 1 thereof, parts of said plate projecting outwardly through the openings in the sides of said sleeve member so as to interlock with the transverse members or bands 2 which extend across said openings, thus forming a rigid abutment or support on said sleeve member for the post member C.

As shown, said plate 4 conforms substantially to the shape in cross-section of the sleeve section B of the strut, being substantially square, and is positioned within said sleeve section with its corners projecting outwardly through the longitudinal openings 3 in the sides of said sleeve section so that they will interlock with the transverse members of bands 2 which connect the angle bars 1 thereof. Also, to render the plate 4 interchangeable so that it may be engaged with different transverse members or bands 2, said plate is so proportioned that it may be inserted into the interior of the sleeve section B through the openings in the sides thereof, between adjacent bands 2.

The particular advantage of this feature of my improved strut or column is that the

post members C may be made of timbers of random lengths, thus providing for using pieces of timber which might otherwise be of little or no value, instead of making said struts or columns of new timbers cut to proper length.

To provide for accurately adjusting the tops of the struts or columns A to bring them to the proper level, the lower ends of the post members C preferably rest upon wedges 5 which in turn rest upon a suitable support or foundation indicated at 6.

Excepting as otherwise herein particularly described and pointed out, the sleeve member B and post member C and associated parts are substantially identical both in construction and as regards the manner of using the same, with the corresponding parts of the strut or column which forms the subject-matter of my said prior Patent No. 1,486,444.

In accordance with my present invention, the strut or column A formed by the sleeve member B and post member C can readily be converted into a **T**-strut by means of the brackets D which are adapted to be removably secured to the upper end thereof, and which are adapted to support a timber 7 of suitable length, which forms the cross-member of said **T** on which the load rests.

While my invention contemplates the use of brackets D of any desired construction, because of its simple construction, small cost of manufacture, strength and light weight, I prefer the form of bracket shown in the drawings and which will now be described, the description referring to said bracket when attached to the strut or column A in use.

The bracket D consists of a beam member *d* adapted to be attached directly to a rigid part of the sleeve member B of the strut, a tension bracing member *d*¹ adapted to rest in contact with the side of the sleeve member B to which the bracket is attached, and diagonal struts or compression members *d*² which connect said beam member *d* and tension member *d*¹ adjacent to their outer ends, said compression members being of such length that they will extend above the upper surface of the beam member *d* and rearwardly beyond the tension member *d*¹, said projecting ends being designated 8 and 9, respectively.

As shown, the beam member *d* consists of angle bars 10 secured together in spaced relation by cross bars 11 riveted or otherwise secured thereto at short distances from their opposite ends, said angle bars being disposed with their flanges extending inwardly and downwardly.

The tension bracing member *d*¹ also consists of angle bars 13, the upper ends of which are secured to the depending flanges of the angle bars 10 and the outer ends of

which are connected by a cross bar 14 rigidly secured thereto, said angle bars being disposed with their flanges extending inwardly and frontwardly, that is away from the sleeve member B. As shown, also, the lower ends of the angle bars 13 are secured together in such relation that the rearwardly projecting ends 9 of the strut or compression members d^2 will embrace opposite sides of the sleeve member B of the strut when said bracket is attached thereto, the rearwardly projecting ends of said struts or compression members operating to engage the lower end of the tension member d^1 positively with the sleeve member B so as to prevent turning of the bracket under load.

The bracket D is adapted to be removably attached to the sleeve member B by means of slots 15 formed in the depending flanges of the angle bars 10 of the beam member d, which are adapted to hook over the upper ends of the flanges of the angle bars 1 forming parts of the sleeve member B, which project over the sides of said sleeve member to which said bracket is to be attached, the inner end of said beam member being made of such width that it will fit loosely between the flanges of the angle bars 1 other than those which the slots 15 are designed to engage.

As shown, the angle bars 1 extend a short distance above the uppermost set of transverse members 2 which connect said angle bars and the flanges of said angle bars over which the slots 15 hook are cut-away flush with the top edges of said transverse members, said slots 15 being of such width that they will receive both the flanges of the angle bars 1 and the transverse members 2 which connect said flanges.

When the flanges to which the brackets D are designed to be attached, are cut-away in the manner described, the upper ends of the other flanges of said angle bars 1 will extend above the upper surface of the bracket D on both sides thereof, as shown at 16.

When it is desired to use the strut A as a T-strut, brackets D are attached to opposite sides thereof in the manner heretofore described and the cross-timber 7 placed in position on the upper surfaces of said brackets, where it will be confined by the projecting upper ends 8 of the struts or compression members d^2 of said brackets and by the upwardly extending flanges 16 of the angle bars 1 of the sleeve member B, which together define a groove or channel on the upper sides of said brackets adapted to receive said timber.

With the described construction it is obvious that by attaching the brackets D to the strut or column A or detaching them therefrom, said strut or column may quickly and conveniently be converted for use either as a plain strut or column, as shown

and described in my said prior Patent No. 1,486,444, or as a T-strut as herein particularly shown and described.

I claim—

1. A strut or column comprising a sleeve member, a post member loosely fitted thereto and adapted to telescope therein, an adjustable stop on said sleeve member which forms a rigid abutment for said post member, a bracket on said sleeve member comprising a beam member, and means for defining a channel on the upper side of the beam member of said bracket adapted to receive a cross-member.

2. A strut or column as specified in claim 1, in which the channel on the beam member of the bracket on said sleeve member is formed by parts of said sleeve member which extend above said beam member.

3. A strut or column as specified in claim 1, in which the bracket on the sleeve member comprises a compression member parts of which extend above the top of the beam member of the bracket on both sides thereof.

4. A strut or column as specified in claim 1, in which the bracket on the sleeve member comprises a compression member, and the channel on the beam member of said bracket is formed by parts of said sleeve and compression members which extend above said beam member on both sides thereof.

5. A strut or column as specified in claim 1, in which the beam member of the bracket 100 consists of rigidly connected angle bars flanges of which extend inwardly over the upper end of the sleeve member proper of the strut or column.

6. A strut or column as specified in claim 1, in which the beam member of the bracket consists of rigidly connected angle bars flanges of which extend inwardly over the upper end of the sleeve member proper of the strut or column, and the compression 110 member of said bracket consists of flanged members secured to opposite sides of the beam member with their flanges disposed outwardly and their upper ends extending above the upper side of said beam member.

7. A strut or column as specified in claim 1, in which the sleeve member proper consists of rigidly connected angle bars flanges of which are cut off below the upper end of said sleeve member, and the other flanges 120 of said angle bars extending above the upper surface of the beam member of the bracket on said sleeve member on both sides thereof.

8. A strut or column as specified in claim 1, in which the sleeve member of the strut consists of rigidly connected angle bars flanges of which are cut off below the upper end of said sleeve member, and the other flanges of said angle bars extending above 125

- the upper surface of the beam member of the bracket on said sleeve member, and said bracket comprises a compression member parts of which extend above the upper surface of the beam member of said bracket on both sides thereof.
9. A strut or column comprising a sleeve member consisting of connected angle bars, transverse members which rigidly connect said angle bars, a post member loosely fitted thereto and adapted to telescope therein, an adjustable stop on said sleeve member which forms a rigid abutment for said post member, a bracket detachably secured to said sleeve member comprising a beam member constructed and arranged to interlock with a rigid part of said sleeve member, and means for defining a channel on the upper side of said beam member adapted to receive a cross-member.
10. A strut or column as specified in claim 9, in which the beam member of the bracket is provided with a hook or hooks adapted to engage the upper ends of the flanges of the angle bars forming parts of the sleeve member of the strut which project inwardly over the sides of said sleeve member to which said bracket is adapted to be attached.
11. A strut or column as specified in claim 9, in which the beam member of the bracket is provided with a hook or hooks adapted to engage the upper ends of the flanges of the angle bars forming parts of the sleeve member which project inwardly over the sides of said sleeve member to which said bracket is designed to be attached, the upper ends of said flanges terminating substantially flush with the topmost transverse member or members which connect said flanges and the hook or hooks on the beam member of said bracket being wide enough to receive both the flange of an angle bar and said transverse member.
12. A strut or column as specified in claim 9, in which the beam member of the bracket is provided with a hook or hooks adapted to engage the upper ends of the flanges of the angle bars forming parts of the sleeve member which project inwardly over the sides of said sleeve member to which said bracket is designed to be attached, the upper ends of said flanges terminating substantially flush with the topmost transverse member or members which connect said flanges and the hook or hooks on the beam member of said bracket being wide enough to receive both the flange of an angle bar and said transverse member, the flanges of said angle bars other than those to which bracket at-

tachments are adapted to be made extending above the upper surface of the beam member of a bracket attached to said sleeve member at both sides thereof, whereby the upper ends of the flanges of the angle bars adapted to be engaged by the hook or hooks on said bracket will be reinforced by transverse members which connect said angle bars.

13. A strut or column as specified in claim 9, in which the beam member of the bracket consists of rigidly connected angle bars disposed with their flanges extending downwardly and inwardly and the hooks for attaching said bracket to the sleeve member proper consist of slots formed in the depending flanges of said angle bars.

14. A strut or column as specified in claim 9, in which the beam member of the bracket consists of rigidly connected angle bars disposed with their flanges extending downwardly and inwardly and the hooks for attaching said bracket to the sleeve member proper consist of slots formed in the depending flanges of said angle bars, and the tension member of the bracket consists of rigidly connected angle bars disposed with their flanges extending inwardly and forwardly.

15. A strut or column comprising a sleeve member, a post member loosely fitted thereto and adapted to telescope therein, a bracket on said sleeve member comprising a beam member and means for defining a channel on the upper side of the beam member of said bracket adapted to receive a cross-member.

16. A strut or column as specified in claim 15, in which the channel on the beam member of the bracket on said sleeve member is formed by parts of said sleeve member which extend above said beam member.

17. A strut or column as specified in claim 15, in which the bracket on the sleeve member comprises a compression member parts of which extend above the top of the beam member on the bracket on both sides thereof.

18. A strut or column as specified in claim 15, in which the bracket on the sleeve member comprises a compression member, and the channel on the beam member of said bracket is formed by parts of said sleeve and compression members which extend above said beam member on both sides thereof.

In witness that I claim the foregoing as my invention, I affix my signature this 19th day of April, A. D. 1923.

NELS L. MALMGREN.
